(57) **CLAIM**

The ornamental design for handpiece for arm sling, as shown and described.

DESCRIPTION

FIG. 1 is a perspective view of a handpiece for arm sling, showing my new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof;

FIG. 7 is a bottom plan view thereof; and,

FIG. 8 is a perspective view of the handpiece for arm sling of FIG. 1, shown in condition of use for clarity of disclosure. The broken lines in the drawings depict environmental structure of the handpiece for arm sling that form no part of the claimed design. The handpiece for arm sling is shown with a symbolic break in its length and in its width. The appearance of any portion of the article between these breakaway lines forms no part of the claimed design.
